UNITED STATES PATENT OFFICE.

LOUIS H. MAIER, OF NEW YORK, N. Y.

MUSICAL INSTRUMENT.

1,034,811.

Specification of Letters Patent.

Patented Aug. 6, 1912.

Application filed November 10, 1911. Serial No. 659,473.

To all whom it may concern:

Be it known that I, LOUIS H. MAIER, a citizen of the United States, and resident of New York city, borough of the Bronx, in the county of New York and State of New York, have invented certain new and useful Improvements in Musical Instruments, of which the following is a specification.

The object of my invention is to support the music rolls in player pianos and analogous instruments within the key bottom in such manner that the music rolls may be pulled out in front of the piano for operating them, and may be pushed back into a space in the key bottom beneath the keys, whereby the music rolls are supported beneath the keys so as not to interfere with the operator.

My invention comprises novel details of improvement and combinations of parts that will be more fully hereinafter set forth and then pointed out in the claims.

Reference is to be had to the accompanying drawings forming part hereof, wherein, Figure 1 is a plan view of a portion of a piano, partly in section, provided with my improvements, showing the latter pulled out in position for use; Fig. 2 is a section on the line 2, 2, in Fig. 1; Fig. 3 is a similar sectional view showing the music roll box pushed back under the keys, also showing a portion of the piano action; Fig. 4 is a section on the plane of the line 4, 4, in Fig. 1; Fig. 5 is a rear view of the music roll box; Fig. 6 is a detail section on the line 6, 6, in Fig. 1; Fig. 7 is a detail cross section on the line 7, 7, in Fig. 1; Fig. 8 is a partly broken perspective view of a portion of the music-roll box-supporting devices; Fig. 9 is a perspective view of a grand piano provided with my improvements, and Fig. 10 is a similar view of an upright piano provided with my improvements.

Similar numerals of reference indicate corresponding parts in the several views.

The numeral 1 indicates a key bed or key bottom of a piano beneath the keys 2.

My improvements may be applied in a grand piano, illustrated in Fig. 9, or in an upright piano illustrated in Fig. 10, or in any analogous musical instrument.

In Fig. 3 I have illustrated part of a piano action, which forms no part of my present invention, and may be of any approved construction adapted to be operated by the keys 2, as well as by a player mecha-

nism not necessary to illustrate. In the example illustrated, however, I have shown rods 4 adapted to operate the keys, said rods passing through suitable guides or openings 60 in the key bottom 1, and adapted to be operated by player mechanism in any well-known manner. 1^x indicates the key-frame carried by bottom 1.

The music-roll mechanism, to which my 65 invention pertains, is arranged as follows: For a suitable depth and width at one edge of the frame, as at the front of the piano, beneath the keys and the key-frame, the bottom board 1 is cut away forming an opening 1^a, adapted to receive the frame or box 5 of the music roll supporting and operating mechanism, whereby said music roll mechanism may be maintained, when not in use, below the keys and partially within the key 75 bottom (see Fig. 3), and when the music roll mechanism is to be used for operating the piano, the frame or box 5 is pulled out in front of the piano (see Figs. 1, 2, 4, 9 and 10).

Frame 5 may be of any suitable construction, and is shown provided with means for supporting the music spool 6 and the takeup spool 7, which carry the music sheet 8. A tracker 9 of suitable construction is also carried by frame 5. Any suitable mechanism 5^a may be provided for operating the music rolls, and having a re-roll finger 5^b. The mechanism I have shown is located within a compartment 5^a of frame 1 (see Fig. 1). 90 The driving shaft 10 of the music roll operating mechanism is carried in suitable bearings on frame 5, and is shown connected by a universal joint 11 with shaft 12 to be operated by a motor, whereby frame 5 may be 95 pulled out and pushed back beneath the keys without interfering with shaft 12.

In order to maintain, in proper positions, the flexible tubes 9^a that connect the tracker orifices with an exhaust chamber 12 (that is 100 shown carried by the key bottom 1), the tubes 9^a are made sufficiently long so as not to be stretched when frame 5 is pulled out to its limit, and in order to support the tubes properly when frame 5 is pushed back beneath the keys, said frame is shown provided with a cross bar 14 that overlies the substantially parallel tubes 9^a, whereby when frame 5 is pushed back beneath the keys the bar 14 will extend into the bights 105 9^b of tubes 9^a (Fig. 3) and thereby support said tubes and keep them from hanging.

- down in the way of the operator. The tubes 9^a where they pass from chamber 12 are shown resting upon a support 15 carried by bottom 1, and by having the support 15 in substantially circular form the tubes 9^a may rest easily thereon and move therearound in curved form so as not to bend the tubes. Bar 14 is shown carried by rods 14^a projecting from the rear of frame 5.
- 10 Frame 5 is suitably carried by key bottom 1 in such manner that it may be properly supported when drawn out from said key bottom and when pushed into the same, and I also provide means to lock said frame to the key bottom in either of said positions. In the arrangement I have illustrated I provide, along each side or edge 1^c of opening 1^a of the key bottom, a channel member 16 within which channel member is slidably supported another channel member 17, having flanges 17^a and stops 17^b at the forward end, the members 17 being connected by a rear cross member or bar 18. Suitable stops are provided to limit the outward movement 25 of channel frame members 17. For this purpose I have shown pins 19 carried by bottom 1 adapted to be engaged by pins 20 carried by cross member 18 (see Figs. 2, 7 and 8). Frame 5 fits freely between the members 16 and 17 and carries at its ends rollers 21 that fit and operate freely within channel member 17, being retained in position by the flanges 17^a and adapted to abut against the end members 17^b and 17^c of members 17 (see Fig. 8). The arrangement is such that when frame 5 is pulled out from the key bottom the rollers 21 will travel freely in channel members 17 until the forward rollers engage the stops 17^b, and thereupon channel members 17 will be pulled outwardly until its stops 20 engage stops 19 and the frame 5 will be in proper forward position. When frame 5 is pushed back into the key bottom, the rollers 21 slide 45 along channel members 17 until the rearward rollers engage stops 17^c, and thereupon the channel members 17 will be pushed back in channel members 16 until frame 5 is in the proper rearward position. To retain frame 5 at the rearward and forward positions I provide the following means: At the back of frame 5 is a longitudinally slidable rod 22 adapted to project beyond one end of said frame to engage holes α , α' in the key bottom (Fig. 1) and at the opposite end of frame 5 is a longitudinally slidable rod 24, whose outer end is adapted to project beyond frame 5 and enter holes γ , γ' in key bottom 1 (Fig. 1). The rods 22 and 24 are 55 preferably located in the recesses a , b , at the back of frame 5, and are shown held in place by straps or the like 26 (see Fig. 5). Rods 22 and 24 are shown respectively pressed outwardly by springs 27 and 28 (see 60 Fig. 5). To operate rods 22 and 24 simul-

taneously, the adjacent bent ends 22^a, 24^a of said rods travel in slots c , d , in the back of wall of frame 5, (Fig. 6) and are engaged by the corresponding ends of a rocker 29, pivoted upon frame 5, as at 30, the free end of rocker 29 being shown connected by link 31 with an arm 32 on a shaft 33 journaled upon the bottom of frame 5 and provided with a handle 34 for operating said shaft. When frame 5 is pushed rearwardly in the key bottom the rods 22 and 24 enter holes α , γ , and when the frame is pulled outwardly the rods 22 and 24 enter the holes α' , γ' . The members 17 are provided with holes α^2 , α^3 adapted to align, respectively, with holes α and γ when frame 5 is at the rearward position, and with holes α' , γ' , when the frame is pulled out, the rods 22, 24 passing through the holes α^2 , α^3 , and locking the members 17 to the members 16. Upon frame 1 are located the tempo fingers 35 and its indicator 35^a, and a button 36, which may be used as a signal button, and the buttons 37, one of which may be used to raise the dampers and the others may be used to raise the hammers of the piano action in separate sections controlled severally by such buttons to reduce the volume of tone, or for any other purpose which may be desired. Such buttons may be connected by flexible tubes with the corresponding mechanism of the piano action in manner shown with respect to the tubes 9^a.

In accordance with my invention it will be observed that the music-roll frame 5, by being located in an opening formed within the key bottom, is thus raised to a convenient height to enable the legs of the operator, when sitting in front of the instrument, to be free without interference from the music box frame, and that the front of frame 5 is adapted to form, with the adjacent portions of the key bottom, a flush finish and appearance, so that frame 5 will not be objectionable in appearance.

While I have used the term "piano" herein, it will be understood that said term is intended to include other musical instruments, such as an organ, having a bottom board analogous to the part 1 which I have herein termed a "key bottom". The term piano would also include a stringed musical instrument having an action to strike the strings but without keys, the action being operated by any desired player mechanism.

Having now described my invention what I claim is:

1. A musical instrument having a key bottom provided with an opening, a frame provided with music roll mechanism located in said opening in the key bottom, and means supporting the frame in the opening to enable the frame to be moved forwardly and rearwardly within said opening.

2. A musical instrument having a key bottom provided with an opening at its forward part, a frame fitted to travel in said opening and provided with means to support music rolls and a tracker, and means supporting the frame to enable the frame to be moved forwardly and rearwardly within said opening.
3. A musical instrument having a key bottom provided with an opening, a frame provided with music roll mechanism located in said opening in the key bottom, and means supporting the frame in the opening to enable the frame to be moved forwardly and rearwardly in said opening.
4. A musical instrument having a key bottom provided with an opening, a frame fitted to travel in said opening and provided with music roll mechanism and a tracker, and means to permit the frame to be moved forwardly and rearwardly within said opening.
5. A musical instrument having a key bottom provided with an opening, a frame provided with music roll mechanism located in said opening in the key bottom, and means to permit the frame to be moved forwardly and rearwardly within said opening, said frame being provided with devices for controlling operation of the instrument.
6. A musical instrument having a key bottom provided with an opening, a frame provided with means to support music rolls located in said opening in the key bottom, and guiding means to maintain said frame in operating position forwardly of said opening.
7. A musical instrument having a key bottom provided with an opening, a frame fitted to travel in said opening and provided with means to support music rolls and a tracker, and means to lock the frame in the rearward and in the forward position.
8. A musical instrument having a piano action, keys, a frame carrying the keys, and a key bottom, the latter being provided with an opening beneath the keys and key frame, a frame fitted to said opening immediately beneath the keys and key frame, and means to support the frame in said opening, said frame being provided with means to support music rolls.
9. A musical instrument having a piano action, keys, a frame carrying the keys, and a key bottom, the latter being provided with an opening beneath the keys and key frame, a frame fitted to said opening immediately beneath the keys and key frame, and means to support the frame in said opening, said frame being provided with music roll mechanism and a tracker.
10. A musical instrument provided with an opening in an edge of its key bottom, a frame to be supported in said opening, said frame having means to support music rolls
- 5 and a tracker, an exhaust chamber carried by the instrument, and means to connect said exhaust chamber with the orifices of the tracker and permit the frame to be moved outwardly relatively to said chamber.
11. A musical instrument having keys, a key bottom provided with an opening, a frame fitted to travel in said opening, means to permit the frame to be drawn outwardly through the opening, said frame having music roll mechanism and a tracker below the keys, flexible tubes connected with the orifices of the tracker, and a chamber connected with the key bottom and with said tubes.
12. A musical instrument having a key bottom provided with an opening, a frame fitted to travel in said opening, means to permit the frame to be drawn outwardly through the opening, said frame having music roll mechanism and a tracker, flexible tubes connected with the orifices of the tracker, and a chamber connected with the key bottom and with said tubes, said frame having means engaging the tubes to support them when the frame is within the rear portion of the opening in the key bottom.
13. A musical instrument provided with an opening, a frame fitted to said opening, means to permit the frame to be drawn outwardly through the opening, said frame having music roll mechanism and a tracker, flexible tubes connected with the orifices of the tracker, and a chamber connected with the key bottom and with said tubes, said frame being provided with a bar overlying the tubes, adapted to support the latter when the frame is at the inner portion of said opening.
14. A musical instrument provided with an opening, a frame fitted to said opening, means to permit the frame to be drawn outwardly through the opening, said frame having music roll mechanism and a tracker, flexible tubes connected with the orifices of the tracker, and a chamber connected with the key bottom and with said tubes, said frame being provided with a bar overlying the tubes and adapted to support the latter when the frame is at the inner portion of said opening, the key bottom having a rest upon which the tubes lie near their inner ends.
15. A musical instrument provided with a key bottom having an opening, a frame having music roll mechanism and a tracker, pairs of members at opposite sides of said opening, one member of each pair being slidable relatively to the other, stops to limit movement of the slidable members, and means movably connecting the frame with the slidable members.
16. A musical instrument provided with a key bottom having an opening, a frame hav-

- ing music sheet mechanism and a tracker, pairs of members at opposite sides of said opening, one member of each pair being 5 slidable relatively to the other, stops to limit movement of the slidable members, and means movably connecting the frame with the slidable members, said means comprising rollers on the frame coacting with the slidable members.
- 10 17. A musical instrument provided with a key bottom having an opening, a frame having music sheet mechanism and a tracker, pairs of members at opposite sides of said opening, one member of each pair being 15 slidable relatively to the other, stops to limit movement of the slidable members, means movably connecting the frame with the slidable members, and stops on the slidable members to limit the outward movement of 20 the frame.
18. A musical instrument provided with a key bottom having an opening, a frame having music sheet mechanism and a tracker, pairs of members at opposite sides of said 25 opening, one member of each pair being slidable relatively to the other, stops to limit movement of the slidable members, means movably connecting the frame with the slidable members, and locking devices carried 30 by the frame adapted to coact with the key bottom to hold the frame in the outward position.
19. A musical instrument provided with a key bottom having an opening, a frame having 35 music sheet mechanism and a tracker, pairs of members at opposite sides of said opening, one member of each pair being slidable relatively to the other, stops to limit movement of the slidable members, means 40 movably connecting the frame with the slidable members, and locking devices carried by the frame adapted to coact with the key bottom to hold the frame in the outward position and in the inward position.
- 45 20. A musical instrument having a key bottom provided with an opening, channel members secured along opposed sides of said opening, channel members slidable in the first named members, means to limit outward movement of the slidable members, a cross bar between said members, a frame, 50 and rollers carried by the frame and coacting with the slidable members.
21. A musical instrument having a key bottom provided with an opening, channel members secured along opposed sides of said opening, channel members slidable in the first named members, means to limit out- 55
- ward movement of the slidable members, a cross bar between said members, a frame, 60 rollers carried by the frame and coacting with the slidable members, and means to lock the frame in the outward position.
22. A musical instrument having a key bottom provided with an opening, channel members secured along opposed sides of said opening, channel members slidable in the first named members, means to limit outward movement of the slidable members, a cross bar between said members, a frame, 65 70 rollers carried by the frame and coacting with the slidable members, and means to lock the frame in the outward and in the inward position.
23. A musical instrument having a key bottom provided with an opening, channel members secured along opposed sides of said opening, channel members slidable in the first named members, means to limit outward movement of the slidable members, a cross bar between said members, a frame, 75 80 rollers carried by the frame and coacting with the slidable members, means to lock the slidable members and the frame to the stationary members. 85
24. A musical instrument having a key bottom provided with an opening, a frame fitted to said opening, means to slidably support the frame in said opening, said frame having music sheet mechanism and a tracker, 90 rods carried by said frame, the key bottom being provided with holes to receive said rods when the frame is in the inner and outer positions, and means carried by the frame for operating said rods. 95
25. A musical instrument having a key bottom provided with an opening, a frame fitted to said opening, means to slidably support the frame in said opening, said frame having music sheet mechanism and a tracker, 100 rods carried by said frame, the key bottom being provided with holes to receive said rods, means carried by the frame for operating said rods, said means comprising a rocker to engage adjacent ends of said rods, 105 a shaft carried by the frame, an arm carried by the frame and connected with said rocker, and a handle for operating said rod.

Signed at New York city, in the county of New York, and State of New York, this 110
8th day of November, A. D. 1911.
